[57] CLAIM

The ornamental design for a colander, substantially as shown.

DESCRIPTION

FIG. 1 is a top perspective view of a colander showing my new design;
FIG. 2 is a front elevational view thereof;
FIG. 3 is a side elevational view thereof;
FIG. 4 is a top plan view thereof;
FIG. 5 is a bottom plan view thereof; and
FIG. 6 is an enlarged cross-sectional view thereof taken along line 6—6 of FIG. 4.
